UNITED STATES PATENT OFFICE.

EDWIN L. BROCKWAY, OF GLENSIDE, PENNSYLVANIA.

CABLE-HANGER.

1,206,203.

Specification of Letters Patent. Patented Nov. 28, 1916.

Application filed September 10, 1915. Serial No. 49,876.

To all whom it may concern:

Be it known that I, EDWIN L. BROCKWAY, a citizen of the United States, residing at Glenside, in the county of Montgomery and 5 State of Pennsylvania, have invented certain new and useful Improvements in Cable-Hangers, of which the following is a specification.

The invention relates to cable hangers 10 such as are used in connection with underground electrical work and has for its principal object to provide cable hangers adapted for detachable, interlocking engagement with standards or uprights, the 15 same being so designed with respect to one another that a hanger may be adjusted vertically of its standard as well as adjusted in an arc of a circle with respect thereto.

Other and further objects of the present 20 invention reside in the providing of a new and novel construction of cable hanger designed to facilitate the hanging of cables irrespective of the angle of approach of a cable; a cable hanger designed to reduce to 25 a minimum the work of hanging cables, and in the providing of a cable hanger which may be easily removed from its standard and a substitution or an adjustment thereof made without disturbing adjacent cables.

30 With these and other objects in view the invention consists of the improvements hereinafter described and finally claimed.

The nature, characteristic features and 35 scope of the invention, will be more fully understood from the following description taken in connection with the accompanying drawings forming part hereof, and in which:

Figure 1, is a perspective view illustrating 40 the manner of installing cable hangers in accordance with the present invention, Fig. 2, is a view in cross-section taken upon the line 2—2 of Fig. 1, but drawn to an enlarged scale, Fig. 3, is a fragmentary view in section illustrating details of construction, and 45 Fig. 4, is a fragmentary view in perspective illustrating a slightly modified form of construction.

In the drawings and referring more particularly to Figs. 1, to 3, inclusive, 10, designates tubular standards or uprights, the ends 50 of which are inwardly bent at 11, and terminate in flat portions 12. The flat portions 12, are bolted or otherwise secured as at 13, to a suitable supporting structure 14. This arrangement forms a simple and inexpen-

sive method of projecting the main portion of a standard or upright 10, free of its supporting structure, to permit hangers being readily attached thereto. The tubular standards are apertured substantially throughout their height as 15, upon their front faces. These apertures are disposed in staggered relation with one another so as to extend partially around the standard faces. This 65 is so that the hangers, about to be described may be adjusted in arcs of circles with respect to the standards as well as vertically thereof.

The hangers are designated 16, and each 70 embraces an arm terminating at its rear end in a hook-like attaching member 17. This hook-like member is cut-away at its lower edge, as at 18, so that the said member gradually tapers to a pointed end 19, which 75 pointed end terminates short of the arm as shown thus providing a space sufficient to permit of the hook-like member encircling a standard 10. In plan a somewhat elliptical shaped space 20, is present, formed by the 80 hook-like member. That part of the hanger, where the member 17, joins the arm 16, which parts are preferably integral, is formed upon an angle terminating in a straight portion 21. This part 21, is provided 85 with a projection or pin 22, which extends into the space 20, before referred to. The arm 16, consists of a rib 23, the top of which terminates in a relatively broad cable support 24, laterally notched as at 25, to 90 accommodate cables 26. The length of the arm and number of notches employed varies according to the character of work being done. In some instances, the notches 25, may be omitted.

In practice, a hook-like member is caused 95 to encircle a standard and the arm 16, moved vertically of the standard and partially rotated with respect thereto until a desired aperture 15, is located. In this movement 100 the arm is slightly tilted upwardly but when the pin or projection enters the aperture selected the arm assumes a horizontal position. The inclined surface before referred to permits of such tilting and keeps the said 105 pin free of the apertures 15, during adjustments.

Among the advantages to be derived by 110 the use of the above described cable hangers mention may be made of the following:— The hangers may be adjusted vertically and in an arc of a circle with respect to their

standards whereby cables may be hung properly irrespective of the angle of approach of such cables. Instead of bending cables to meet the hangers, the hangers may 5 be partially rotated to approach the cables. The hangers being interchangeable, they may be readily removed and others substituted without interference with the supported cables. Because the hangers may be 10 partially rotated to approach a cable, flexibility of the cables is maintained and the work of hanging cables reduced to a minimum.

In Fig. 4, there is disclosed a somewhat modified form of the invention. The standard 30, in this instance comprises a channel rail, the front face of which is provided with a series of apertures 31. The hanger 32, in turn is provided with a hook-like member 33, which is up-turned as shown. The lower part of the hook-like member 33, adjacent the rear end of the arm portion of the hanger, is notched as at 34. When the hook-like member 33, engages an aperture in the standard 30, this notch seats itself with respect to said apertured portion of the standard and constitutes an interlocking of the parts.

In both of the above described hangers it 30 will be observed that the hook-like members each possess the same principle of interlock, to wit:—the tapered portion of each hook-like member is located to the rear of a standard and bears against such part of 35 the standard, with the rear part or heel of the hanger arm abutting against the standard face, the points of pressure being in two planes, and the hanger in each instance being provided with an interlocking part 40 to prevent the hanger sliding downwardly upon its standard.

What I claim is:

1. A cable hanger embracing a standard of substantially circular cross-section the 45 front face of which is provided with a series of staggered apertures extended partially around the standard face and a series of interchangeable hangers supported upon said standard for adjustment in arcs of 50 circles therearound in a horizontal plane as well as for vertical adjustment thereon, each hanger embracing a one-piece article consisting of an arm the top of which is laterally grooved for cable accommodation which 55 arm terminates in a hook-like member gradually tapering to a pointed end, the hook-like member abutting against the standard back and the heel portion of said arm abutting against the standard face, means 60 being present upon said hanger for engaging within an apertured portion of the standard to interlock the parts.

2. A cable hanger embracing a tubular

standard the front face of which is provided with a series of apertures arranged in staggered relation partially around said standard face and a series of interchangeable hangers supported upon said standard for adjustment in arcs of circles therearound in a horizontal plane as well as for vertical 70 adjustment thereon, each hanger embracing a one-piece article consisting of an arm the top of which is laterally grooved for cable accommodation which arm terminates in a hook-like member gradually tapering 75 to a pointed end, which hook-like member encircles the standard with its pointed end abutting against the standard back and the heel portion of the arm abutting against the standard face and a projection carried 80 by said heel portion for engagement with an apertured portion of the standard to interlock the parts.

3. A cable hanger embracing in combination a supporting structure, a standard of 85 tubular formation supported thereby and at least a portion thereof spaced therefrom, the front face of said standard being provided with a series of apertures disposed in staggered relation and a series of interchangeable hangers supported by said standard 90 each hanger embracing a one-piece article consisting of an arm the top of which is laterally grooved for cable accommodation which arm terminates in a hook-like 95 member gradually tapering to a pointed end free of the heel portion of said arm, which hook-like member encircles the standard and abuts against the back thereof and the heel portion of the arm abutting against 100 the standard face which heel portion is inclined and terminates at its base in a flat portion provided with a projection for engagement with an apertured portion of the standard to interlock the parts. 105

4. A one-piece hanger for cables embracing an arm consisting of a rib carrying at its top a horizontally, relatively broad portion, grooved laterally for cable accommodation, the heel portion of said arm being 110 inclined downwardly and terminating in a vertical portion which heel portion has extended therefrom in a horizontal plane a hook-like standard encircling member which gradually tapers to a pointed end free of 115 the heel portion and a standard engaging pin projected from the said vertical portion of the heel of the arm.

In testimony whereof, I have hereunto signed my name in the presence of two witnesses. 120

EDWIN L. BROCKWAY.
